DISPLAY RACKS

Victor R. Romero, Albion, Mich., assignor to Union Steel Products Company, Albion, Mich.
Filed Dec. 18, 1961, Ser. No. 159,953
4 Claims. (Cl. 103—28)

This invention relates to display racks.

The main objects of this invention are:

First, to provide a rack for displaying dishes and the like which may be formed of relatively light stock and is strong and rigid and capable of supporting relatively heavy loads.

Second, to provide a display rack adapted to receive a plurality of plates, saucers, handled cups and the like.

Third, to provide a display rack adapted for the above indicated purposes which is attractive in appearance.

Fourth, to provide a display rack having the above stated advantages which may be economically produced, is strong and rigid and one in which a plurality of the racks may be nested for storage or shipment.

Objects relating to details and economies of the invention will appear from the description to follow. The invention is defined and pointed out in the claims.

A preferred embodiment of the invention is illustrated in the accompanying drawing, in which:

FIG. 1 is a perspective view of a rack embodying applicant's invention with some dishes or receptacles conventionally illustrated thereon.

FIG. 2 is a plan view.

FIG. 3 is a fragmentary end elevational view.

FIG. 4 is a fragmentary view in longitudinal section on a line corresponding to line 4—4 of FIG. 2.

The embodiment of applicant's invention illustrated is designed for the displaying of tableware and the manner of positioning the tableware thereon is indicated in FIG. 1, the tableware being conventionally illustrated; plates 1, saucers 2 or the like and cups 3 being conventionally illustrated in FIG. 1.

The applicant's display rack includes a frame comprising parallel side members 4 and end members 5, these desirably being formed of one continuous strand of metal, the joint for the ends not being illustrated. The side members 4 have downwardly offset intermediate portions 6 of substantial length, the portions 7 of the offsets being substantially vertical in the embodiment shown, although they may be inclined.

The longitudinal rack members 8 are laterally spaced relative to each other and to the side members 4 and have offsets 9 therein corresponding to the offsets 7. The ends of these longitudinal members 8 are disposed on the underside of and fixedly secured, desirably by welding to the end members 5.

A second series of longitudinal members 10 are disposed between the frame side members and the first series of longitudinal members 8 and these have downwardly offset portions 11 corresponding to the downwardly offset portions of the frame side members and members 8. However these members 10 terminate in spaced relation to the end members 5 and in upwardly facing hooks 12 which are downwardly offset relative to the end members 5 and the members 8, see FIGS. 1 and 4.

Crossbars 13 are disposed below the longitudinal members 8 and 10 desirably at the juncture of the hooks with the members 10, as is illustrated in FIG. 4. The hooks are spaced from the underside of the longitudinal members 8 to permit engagement of the handles of cups therewith, as is illustrated in FIG. 1.

The downwardly offset portions provide shelf-like supports for the dishes 1 and the portion of the rack at the outer side of the downwardly offset portion provides a support for dishes such as 2.

2

In the embodiment illustrated the leg members designated generally by the numeral 14 are of inverted U-shape stock provided with crossbars 15 which are fixedly secured to the downwardly extending reaches 9 and 11 of the longitudinal members 8 and 10, the legs 16 in the embodiment illustrated being disposed in diverging relation. This provides a structure which is very strong and rigid in proportion to the gauge of stock used which is desirably of wire plated after forming but they may be provided with any desired coating. As stated, the racks embodying applicant's invention are capable of carrying heavy loads. The crossbars 13 serve to connect the ends of the longitudinal members 10 to the members 8, the ends of which are secured to the ends of the frame. The crossbars 10 are positioned so that the hooks are not distorted by articles placed thereon or by stresses to which they may be subjected to.

I have illustrated my invention in a desirable commercial embodiment. I have not attempted to illustrate a modification adapted for particular goods to be displayed as it is believed this disclosure will enable those skilled in the art to embody or adapt the invention as may be desired.

Having thus described the invention, what is claimed as new and desired to secure by Letters Patent is:

1. A display rack of the class described comprising a frame having integral substantially parallel side members and end members, the side members having downwardly offset intermediate portions of substantial length, a first series of laterally spaced longitudinal members having downwardly offset intermediate portions corresponding to the downwardly offset portions of said frame side members and having their ends fixedly secured to the said frame end members, a second series of longitudinal members disposed between said frame side and said first series of longitudinal members in laterally spaced alternate relation thereto and having corresponding downwardly offset intermediate portions and terminating at their ends in downwardly offset upwardly facing hooks disposed inwardly relative to the said frame end members with their tips disposed below the plane of said first series of longitudinal members, crossbars disposed on the underside of and fixedly secured to said first and second series of longitudinal members at the inner sides of said hooks, and inverted U-shaped leg members disposed with their bight portions on the outer sides of the upright portions of said downward offsets of said frame side and said longitudinal members and fixedly secured thereto.

2. A display rack of the class described comprising a frame having integral substantially parallel side members and end members, the side members having downwardly offset intermediate portions of substantial length, a first series of laterally spaced longitudinal members having downwardly offset intermediate portions corresponding to the downwardly offset portions of said frame side members and having their ends fixedly secured to the said frame end members, a second series of longitudinal members disposed between said frame side and first series of longitudinal members in laterally spaced relation thereto and having corresponding downwardly offset intermediate portions and terminating at their ends in downwardly offset upwardly facing hooks disposed inwardly relative to the said frame end members with their tips disposed below the plane of said first series of longitudinal members, and inverted U-shaped leg members disposed with their bight portions on the outer sides of the upright portions of said downward offsets of said frame side and said longitudinal members and fixedly secured thereto.

3. A display rack of the class described comprising a frame having integral substantially parallel side members and end members, the side members having down-

wardly offset intermediate portions of substantial length, a first series of laterally spaced longitudinal members having downwardly offset intermediate portions corresponding to the downwardly offset portions of said frame side members and having their ends fixedly secured to the said frame end members, a second series of longitudinal members disposed between said frame side and first series of longitudinal members in laterally spaced relation thereto and having corresponding downwardly offset intermediate portions and terminating at their ends in downwardly offset upwardly facing hooks disposed inwardly relative to the said frame end members with their tips disposed below the plane of said first series of longitudinal members, and inverted U-shaped leg members disposed with their bight portions on the outer sides of the upright portions of said downward offsets of said frame side and said longitudinal members and fixedly secured thereto with their legs positioned outwardly relative to said frame side members and in diverging relation.

4. A display rack of the class described comprising a frame having laterally spaced side members and end members fixedly connecting said side members, a first series of laterally spaced longitudinal members having their ends fixedly secured to said frame end members, a second series of longitudinal members disposed between said frame side and said first series of longitudinal mem-

bers in laterally spaced alternating relation thereto and terminating at their ends in upwardly facing hooks which are downwardly offset relative to said first series of longitudinal members and with their tips in a plane below the plane thereof, crossbars disposed on the underside of and fixedly secured to said first and second series of longitudinal members at the inner side of but adjacent to said hooks, other crossbars spaced inwardly relative to said aforementioned crossbars and fixedly secured to said side members and said first and second series of intermediate members and provided with downwardly projecting legs.
